PORATION OF NEW JERSEY.

METHOD OF MAKING SHOES.

1,406,280.

Specification of Letters Patent. Patented Feb. 14, 1922.

Application filed March 28, 1917. Serial No. 157,961.

To all whom it may concern:

Be it known that I, CHARLES F. PYM, a subject of the King of England, residing at Lynn, in the county of Essex and State of Massachusetts, have invented certain Improvements in Methods of Making Shoes, of which the following description, in connection with the accompanying drawings, is a specification, like reference characters on the drawings indicating like parts in the several figures.

This invention relates to the manufacture of boots and shoes, and particularly to the operation of securing the upper in conformity to the last about the end portion of the last. In the lasting operation as usually carried out, particularly where the innersole or the sole of the shoe, hereinafter termed generically the sole, is provided with an upper attaching rib or shoulder, it is a common practice to apply a binder about the upper along the margin of the forepart of the sole to retain the upper in lasted position. In practice the binder is usually wrapped about the margin of the upper at the end of the shoe and secured in position by twisting its ends about anchor tacks driven in the margin of the sole at opposite sides. It is an object of this invention to provide an improved method in the use of which the upper may be effectively secured in conformity to the last at the end of the shoe with greater facility and rapidity than heretofore and with improved results in the manufacture of the shoe.

In accordance with the method of this invention, in one important aspect, the upper is secured at the end of the shoe by applying a binder to the shoe and forcing a portion or portions, for example the ends, of the binder into the shoe materials in a novel manner such as to anchor the binder securely in place while leaving it in condition to be readily detached from the shoe when required without damage to the shoe materials. The best results may be secured, particularly on work in which the sole has an upper attaching rib or shoulder, by forcing the ends of the binder into the shoe materials in directions substantially parallel to the plane of the shoe bottom with the ends extending laterally of the shoe in such angular relation to the longitudinal median line of the shoe as to prevent them from being

pulled out by the strain of the upper materials. The method may be conveniently carried out by preparing a binder with in-turned ends, and it may be also a curved intermediate portion, applying the binder first to the end of the shoe and forcing it into holding relation to the upper at that point, and then forcing the ends of the binder into the materials at the sides of the shoe. In order to prevent the projections or ends of the binder from being unduly deflected toward the rear end of the shoe as they are forced into the shoe materials they may be turned to form angles slightly less than right angles with the adjacent portions of the binder; and further insurance of the proper location of the end portions of the binder as they are driven may be afforded by beveling the ends on their outer sides thus rendering the shoe materials effective, by their pressure upon the beveled surfaces, with a tendency to incline the ends of the binder forwardly toward the toe end of the shoe. The inturned ends of the binder may be of such length as may be desired, to cause them to project to a greater or less extent into or through the shoe materials. It is further contemplated that under some conditions it will be advantageous to bend or deflect the projections or ends of the binder, as herein illustrated, in such manner as to dispose them in acute angular relation to adjacent portions of the binder when they are in their holding positions in the shoe. For greater security against displacement of the binder on some classes of work, portions of the upper may be additionally fastened to the sole. For example, in the practice herein illustrated fasteners, hereinafter referred to generically as tacks, may be driven, in accordance with a further step of the method, through the upper and into the sole in such relation to the ends of the binder as to prevent the ends from being pulled out by the outward lateral strain of the upper materials.

The invention further provides, as an article of manufacture, a novel binder for use in securing shoe materials in lasted position.

For the purpose of pointing out more clearly and in detail one manner in which the method of this invention may be practised, the drawings show portions of an ap-

paratus which may be used in carrying out the method, but it will be understood that the method is not dependent upon the use of any particular apparatus.

5 In the drawings;

Fig. 1 shows a binder as it may be prepared for application to a shoe in accordance with the method of this invention,

10 Fig. 2 is a view on a relatively smaller scale than Fig. 1, showing the forepart of a shoe with the upper drawn over the last by the usual upper pulling grippers, together with end wiper mechanism and binder applying means,

15 Fig. 3 is a view similar to Fig. 2, showing the wipers closed over the margin of the sole, the binder applied against the end of the toe, and the ends of the binder about to be driven into the materials,

20 Fig. 4 is a view similar to Fig. 3, showing the ends of the binder fully driven and also tacks driven in position to hold the upper, adjacent to the binder ends, from outward displacement transversely of the last,

25 Fig. 5 illustrates the angular relation which the end portion of the binder may assume to the rib of the sole,

30 Fig. 6 is a sectional view illustrating the relation of the end portion of the binder shown in Fig. 5 to the plane of the sole,

Fig. 7 shows the forepart of the lasted shoe with the binder in place, and

35 Figs. 8 and 9 show tacks driven in different locations for further insuring that the ends of the binder shall not be displaced.

40 The binder, shown in Fig. 1, may be formed, for example, from a piece of wire of suitable length to permit the binder to extend around the upper materials adjacent to the rib of the sole at the toe end of the shoe, and a considerable distance rearwardly along the sides. In carrying out the method

45 of the invention the binder may conveniently be shaped as shown in Fig. 1 before it is applied to the shoe. As thus shaped it is bowed at 2 in its intermediate portion to approximate the contour of the toe end of the rib of the sole in the plane of the sole, and is provided with ends 4 inturned to form

50 with the body portion of the binder angles which are advantageously slightly smaller than right angles, the end portions 4 also being beveled at 6 on their outer sides to form points.

55 The binder may be conveniently applied to the shoe in connection with the operation of wiping the upper materials over the margin of the shoe sole in the manner usual in machines for lasting or for pulling over and

60 lasting the upper. If the invention is practised in connection with pulling-over and lasting operations performed in immediate sequence, the upper will be tensioned over the forepart of the last at the end and sides and may then be wiped inwardly over the

feather of the sole around the toe and carried inwardly and secured by tacks against relaxing outwardly at the sides of the forepart, all as explained for example in United States Letters Patent No. 1,135,950, 70 granted on April 13, 1915 upon the application of R. F. McFeely, while in place of the use of tacks to secure the upper in lasted position around the toe a binder will be applied in accordance with the method of this 75 invention. An important object in the use of the toe binder is to prevent the tensioned and overwiped upper from relaxing forwardly over the end and outwardly at the sides of the toe, and in accordance with one 80 aspect of this invention this result is secured by applying the binder around the toe and inserting its ends in the upper at the sides of the toe in such manner as to hold the binder, and therefore the upper confined by 85 it, from forward and outward displacement. For this purpose it is preferable that the binder ends be made to engage the upper near the side tacks which prevent the tensioned upper from pulling outwardly at the 90 sides of the forepart back of the toe. If the pulling-over operation is performed separately from the lasting operation, the shoe usually comes to the lasting machine with the upper held under tension at the sides of 95 the forepart by the described side tacks and held under tension around the toe by pulling-over tacks which it is customary to remove before wiping in and binding the upper at the toe. The binding-in procedure in 100 accordance with this method is substantially the same whether practised in connection with pulling-over and lasting operations performed immediately in sequence or in connection with a lasting-operation entirely 105 separate from any pulling-over operation, the interval elapsing between the upper tensioning and the toe wiping and binding operations, and the relative timing of the toe binding and side tack driving operations 110 being immaterial as far as this invention in its broader aspects is concerned.

115 In carrying out the operations above referred to the upper may be pulled by grippers such as 5, (Fig. 2) and the tacks inserted by tackers such as 7, and toe embracing wipers 8 may be used, these wipers being mounted to swing about a pivot 10 at their front ends and movable bodily toward the shoe to force the upper into the angle 120 between the rib and the feather of the sole at the toe end and also about their pivot to crowd the upper into the angle along the sides. Below the wipers 8 are end embracing members 12 which are pivoted at 13 and arranged to be closed against the shoe with their upper surfaces substantially in the plane of the surface of that portion of the upper which is wiped down upon the margin of the sole, the members 12 being spaced 130

from the wipers 8 a distance substantially equal to the thickness of the wire binder, or but slightly greater, thus providing a recess in which the binder is to be placed prior to the lasting operation. It will be noted that the binder as thus positioned is substantially flush with the edge of the wipers adjacent to the pivot 10, while the side and end portions are retracted to cause the points of the binder to clear the upper materials during the operation of the wipers. Mounted to swing about pivots 15 in the spaces between the members 8 and 12 are driver plates 14 which may be operated at the proper time in any suitable way, as by pusher bars 16, to force the ends 4 of the binder into the shoe materials.

The binder, which may have been previously bowed as shown in Fig. 1 or may be bent by the operator to conform it substantially to the contour of the shoe, is placed in position between the shoe embracing members 12 and the wipers 8 as shown in Fig. 2, and after the upper has been pulled, the members 12 and the wipers are forced rearwardly of the shoe to embrace the upper about the toe and to lay the upper over the margin of the sole *a* and force it against the shoulder or rib *b* at the extreme toe end of the shoe, the intermediate portion of the binder thus being forced inward against the upper. The wipers 8 are also swung about their pivots, either during their rearward movement or subsequently, to force the upper materials along the sides of the forepart of the shoe into the angle between the feather and the rib of the sole, the position of the parts at the end of this stage of the operation being illustrated in Fig. 3. The driver plates 14 are then operated by the bars 16, while the upper is held firmly by the wipers in lasted position, to crowd the binder against the upper at the sides and to force the ends of the binder into the upper materials, as shown in Fig. 4, and advantageously but not necessarily into the rib or shoulder of the sole as shown more clearly in Fig. 5, the wipers then being withdrawn and leaving the toe of the upper bound in place as illustrated in Fig. 7.

Tacks, as hereinbefore explained, are preferably driven through the upper into the sole at the sides of the toe or the forepart to take the lateral outward strain of the upper. These tacks may be driven adjacent to each end portion of the binder, as shown in Fig. 4, and may include a locking tack applied outside the end portion of the binder as shown in Fig. 8, or a tack driven into the rib of the sole inside of the binder, as shown in Fig. 9, to assist in holding the upper materials against lateral outward strain and insure that the ends of the binder shall not be drawn out of effective holding position. Where the method is carried out by the

aid of a pulling-over and lasting machine these tacks may be driven by the usual side tacking instrumentalities of such machine suitably arranged to drive the tacks in the required positions. Experience has demonstrated, however, that with the ends of wire binders properly angled a locking tack such as shown in Fig. 8, or a tack driven inside of the binder as shown in Fig. 9, is unnecessary on the usual lines of work. 70 75

As previously intimated, it is desirable to prevent the projections or ends of the binder from being unduly deflected toward the rear end of the shoe as they are forced into the shoe materials. By reference to Fig. 3 it will be evident that the inward movement of the portion of the binder at the side of the shoe is virtually a swinging movement about an axis near the toe end of the shoe, and it will be clearly understood therefore that, after the binder has been forced into holding position at the toe end, if the ends of the binder were turned at right angles to the body portion the tendency would be for the ends, after engaging the materials, to be turned 90 backwardly toward the rear of the shoe during their continued inward movement. To counteract such tendency each end of the binder, in carrying out the method in the manner illustrated, is turned to form an angle slightly smaller than a right angle with the body portion, thus permitting the end of the binder to be forced into the materials in the manner contemplated without being bent rearwardly, the angle being nearly a right angle, however, to avoid any tendency to loosen the binder about the shoe during the driving movement. It will be evident that the required conditions are satisfied if the point of the binder first penetrates the stock at a distance from the toe end of the shoe, measured along the upper adjacent to the rib of the sole, equal to the length of that portion of the binder which extends from the toe end to the point where its end is inturned. The bevel on the outer side of the end portion of the binder further insures that the end shall not be bent backward in the driving operation, and this bevel moreover has a tendency to turn the 115 end of the binder forwardly during its continued movement after it has entered the stock. The angle or the bevel, or both, may be such that the end portion of the binder will automatically assume a final position 120 as shown in Fig. 5, in which the end is inclined forwardly and performs the function of a hook to hold the binder against the forward strain of the upper, while this forward strain moreover tends to hold the ends of 125 the binder tightly in the stock against any tendency for the ends to be withdrawn by the lateral outward strain of the upper.

As previously pointed out, the end portions of the binder may be of such length 130

as may be found most suitable in practice, having regard to the particular class of work to be operated upon. On some lines of work penetration of the upper materials by 5 the ends of the binder without engagement with the sole will be found sufficient to hold the binder in place, while on other lines of work it may be preferable to provide binder ends of sufficient length to penetrate the rib 10 or shoulder of the sole to a greater or less extent or to project through the rib as herein shown.

It will be evident that in a shoe lasted in accordance with the method of this invention 15 the binder may be removed, after the upper has been permanently fastened to the sole, simply by pulling out the ends, an operation which may be performed quickly and without damage to the shoe.

20 While the drawings illustrate the invention by reference to the manufacture of a shoe of the welt type, it should be understood that this is solely for purposes of illustration and is not to be regarded as import- 25 ing any limitation of the scope of the invention, since it will be readily recognized that the invention in its broader aspects is not limited in utility to the manufacture of shoes of the welt type but is applicable to 30 the manufacture of various kinds of shoes.

It should be understood that the term "rib," similarly to the term "sole," is used in the claims in a generic sense, and is intended to refer to that portion of the sole 35 which provides an abutment against which the margin of the upper is secured in lasted position, and except where required by the context is not to be construed as limited in meaning to an abutment of the particular 40 form which is characteristic of a welt shoe.

Features of the apparatus herein shown are claimed in a co-pending application Serial No. 186,314 filed on August 15, 1917.

Having explained the nature of the invention and set forth fully how it may be practised, what I claim as new and desire to secure by Letters Patent of the United States is:

1. That improvement in methods of making shoes which consists in working the forepart of an upper into lasted position over the margin of a sole, applying a binder about the upper on the margin of the sole, forcing the ends of the binder into the shoe materials, and leaving said ends directed laterally of the shoe.

2. That improvement in methods of making shoes which consists in working the forepart of an upper into lasted position over the 60 margin of a sole, applying a binder about the upper on the margin of the sole, forcing the ends of the binder into the shoe materials in directions substantially parallel to the plane of the sole, and leaving the binder 65 with its end portions in acute angular rela-

tion to the portions along the sides of the shoe.

3. That improvement in methods of making shoes which consists in working the forepart of an upper over a last and into the 70 angle between the feather and the rib of a sole, applying a binder to the end of the shoe in said angle, forcing the ends of the binder through the upper and into the rib of the sole in directions substantially parallel to the 75 plane of the shoe bottom, and leaving said ends directed laterally of the shoe.

4. That improvement in methods of making shoes which consists in working the forepart of an upper into lasted position over the 80 margin of a sole, preparing a binder with end portions disposed in angular relation to its body portion, applying the binder about the upper on the margin of the sole, and forcing the end portions of the binder into the shoe materials to holding positions in which the ends are directed laterally of the shoe and inclined toward the toe end of the 85 shoe.

5. That improvement in methods of making shoes which consists in working an upper into lasted position about the end of a last, preparing a curved binder with in-turned ends, applying the binder to the upper at the end of the shoe, forcing the ends of the binder into the shoe materials, and leaving the ends projecting laterally of the shoe in a plane substantially parallel to the 90 plane of the shoe bottom.

6. That improvement in methods of making shoes which consists in working an upper over the end of a last and into the angle between the feather and the rib of a sole, preparing a curved binder with in-turned ends, applying the intermediate portion of the 100 binder in said angle at the end of the shoe, and forcing the ends of the binder through the upper and into the rib of the sole to holding positions in which the ends are directed laterally of the shoe.

7. That improvement in methods of making shoes which consists in working an upper into lasted position about the forepart of a last and over the margin of a sole, applying a binder about the upper on the margin of 115 the sole, and forcing the ends of the binder into the shoe materials while causing said ends to be deflected toward the toe of the shoe by their engagement with said materials.

8. That improvement in methods of making shoes which consists in working an upper into lasted position about the end of a last, preparing a binder with end portions turned inwardly to form acute angles with its body 125 portion, applying said binder to the end of the shoe, and forcing the ends of the binder into the shoe materials.

9. That improvement in methods of making shoes which consists in working an upper 130

- into lasted position about the forepart of a last, preparing a binder with end portions turned inwardly to form acute angles with its body portion, applying the binder to the 5 end of the shoe, and forcing the end portions of the binder into the shoe materials to holding positions in which the ends of the binder are directed laterally of the shoe.
10. That improvement in methods of making shoes which consists in working an upper into lasted position about the end of a last, preparing a binder with end portions turned to form acute angles with its body portion, applying the binder to the upper with its 10 intermediate portion in holding relation to the upper at the end of the shoe, and then forcing the ends of the binder into the shoe materials in directions substantially parallel to the plane of the shoe bottom.
15. That improvement in methods of making shoes which consists in working an upper over the end of a last and into the angle between the feather and the rib of a sole, preparing a binder with end portions turned 20 to form acute angles with its body portion, applying the binder to the upper and forcing the intermediate portion of the binder into said angle at the end of the shoe, and then forcing the portions of the binder at the 25 sides of the shoe inward into said angle to cause the end portions to penetrate the upper and the rib of the sole.
20. 11. That improvement in methods of making shoes which consists in working an upper into lasted position about the forepart of a last, preparing a binder having its end portions inturned and beveled on their outer sides in such manner as to cause said portions to be deflected by engagement with the 30 shoe materials, applying the binder to the end of the shoe, and forcing the ends of the binder into the shoe materials in directions to cause said ends to be deflected toward the toe of the shoe by the action of the 35 materials on said beveled sides.
35. That improvement in methods of making shoes which consists in working an upper into lasted position about the end of a last, preparing a binder having its ends inturned and beveled on their outer sides only to form points, applying the binder with its 40 intermediate portion in holding relation to the upper at the end of the shoe, and forcing said ends into the shoe materials in directions substantially parallel to the plane of the shoe bottom.
45. That improvement in methods of making shoes which consists in working an upper into lasted position about the end of a last, applying a binder about the upper and forcing the ends of the binder into the shoe materials in directions transverse to the longitudinal median line of the shoe, and driving fasteners in such relation to the ends 50 of the binder as to prevent said ends from being withdrawn by the strain of the materials.
50. That improvement in methods of making shoes which consists in working an upper into lasted position about the end of a last 70 and over the margin of a sole on the last, applying a binder about the upper at the end of the shoe and forcing the ends of the binder into the materials at opposite sides of the shoe in direction substantially parallel to the plane of the sole, and driving fasteners in such position as to hold the upper against lateral outward strain adjacent to the ends of the binder.
55. That improvement in methods of making shoes which consists in working an upper into lasted position over the end of a last and into the angle between the feather and the rib of a sole, applying a binder about the end of the shoe in said angle and forcing 80 the ends of the binder through the upper and into said rib, and driving fasteners through the upper and into said rib adjacent to each end of the binder to hold the upper against lateral outward strain.
60. That improvement in methods of making shoes which consists in tensioning an upper forwardly over the forepart of a last at the end and transversely across the last at the sides, wiping the upper over the sole 90 around the toe, applying a binder around the toe and inserting its ends into the upper in substantially parallel relation to the plane of the sole to hold the overwiped upper from relaxing forwardly over the toe, and driving 100 fasteners to hold the transversely tensioned upper from relaxing laterally outward over the sides of the forepart adjacent to the binder ends.
65. That improvement in methods of making shoes which consists in conforming an upper to a last round the end portion of a shoe, applying a binder to the upper round the end of the shoe, and anchoring the binder by forcing a portion of it into the shoe 105 materials to a holding position in which said portion is directed laterally of the shoe in acute angular relation to the body portion of the binder.
70. That improvement in methods of making shoes which consists in conforming an upper to a last round the end portion of a shoe, applying a binder to the upper round the end of the shoe, and anchoring the binder by forcing portions thereof into the shoe 110 materials at opposite sides of the shoe to holding positions in which said portions are directed laterally of the shoe.
75. That improvement in methods of making shoes which consists in conforming an upper to a last round the end portion of a shoe, applying a binder to the upper round the end of the shoe, and forcing the ends of the binder into the shoe materials to holding 115 positions in which they are directed in acute 120
80. That improvement in methods of making shoes which consists in conforming an upper to a last round the end portion of a shoe, applying a binder to the upper round the end of the shoe, and forcing the ends of the binder into the shoe materials to holding 125 positions in which they are directed in acute 130

- angular relation to the portions of the binder adjacent to said ends.
21. That improvement in methods of making shoes which consists in conforming an upper to a last round the end portion of a shoe, applying a binder to the upper round the end of the shoe, and forcing the ends of the binder into the shoe materials in directions substantially parallel to the plane of the sole to holding positions in which they are directed laterally of the shoe in acute angular relation to the portions of the binder adjacent to said ends. 65
22. That improvement in methods of making shoes which consists in conforming an upper to a last round the end portion of a shoe, applying a binder to the upper about the end of the shoe, forcing a portion of the binder into the shoe materials laterally of the shoe to anchor the binder, and additionally fastening the upper to the sole adjacent to said portion of the binder to prevent displacement of the binder. 70
23. That improvement in methods of making shoes which consists in conforming an upper to a last round the end portion of a shoe, applying a binder to the upper about the end of the shoe, forcing the ends of the binder into the shoe materials in directions substantially parallel to the plane of the sole to holding positions in which said ends are directed laterally of the shoe, and additionally fastening the upper to the sole adjacent to the ends of the binder to prevent said ends from being withdrawn by the strain of the upper materials. 75
24. As an article of manufacture, a toe binder for shoes comprising a wire of suitable length to extend around the upper materials at the end of a lasted shoe and along the sides of the shoe, said wire having its end portions projecting at acute angles to the body of the wire in directions to permit said ends to be forced into the materials in substantially parallel relation to the plane of the shoe sole. 80
25. As an article of manufacture, a toe binder comprising a wire having its end portions inturned and beveled on their outer sides in such manner as to cause said end portions to be deflected forwardly by their engagement with the shoe materials. 85
26. As an article of manufacture, a toe binder comprising a wire of suitable length to extend around the upper materials at the end of a lasted shoe and along the sides of the shoe, said wire having its end portions projecting at acute angles to the body of the wire in directions to permit said ends to be forced into the materials in substantially parallel relation to the plane of the shoe sole, said end portions being beveled on their outer sides in such manner as to cause said 90
- end portions to be deflected forwardly by their engagement with the shoe materials. 65
27. In a toe binder, the combination with a body portion, of an end portion bent to form an acute angle with said body portion and adapted to be inserted in the shoe materials in substantially parallel relation to the plane of the shoe bottom. 95
28. A toe binder comprising a body portion, and inturned end portions adapted to be inserted in the shoe materials in substantially parallel relation to the plane of the shoe bottom and beveled on their outer sides only for sharpening the ends. 100
29. A binder for holding an upper in lasted position round the end of a shoe comprising a strand of flexible material of suitable length to extend round the end of the shoe and having projections disposed in acute angular relation to the body of the binder and inclined toward each other, to adapt them to be hooked into portions of the upper materials upstanding from the plane of the shoe bottom at the opposite sides of the shoe to anchor the binder to the shoe. 105
30. That improvement in methods of making shoes which consists in conforming upper materials to the contour of the end portion of a last or form with the margin of said materials upstanding from the bottom face of said last or form, applying a binder round said upstanding margin and catching its end portions in the upstanding upper materials, and inserting fasteners in the work at the outer sides of the end portions of the binder to hold them caught in the upper materials. 90
31. That improvement in methods of making shoes which consists in conforming upper materials to the contour of the end portion of a last or form with the margin of said materials upstanding from the bottom face of said last or form, providing a binder with projections adapted to catch in the upstanding upper materials, applying the binder round said upstanding margin with its projections engaging the upstanding materials, and inserting fasteners in the work at the outer side of the binder to hold it with its projections caught in said materials. 95
32. That improvement in methods of securing upper materials in lasted relation to a sole which consists in applying a binder round the end of the upper and securing the end of the binder by forcing it into the upper in a direction substantially parallel to the plane of the sole to a holding position in which it extends substantially in the direction of its penetration of the materials. 110
- In testimony whereof I have signed my name to this specification. 115
